IMPROVED METHODS OF MAKING ELECTRIC
DISCHARGE DEVICE ENVELOPESMonte W. Edwards and Martin O. Murphy, Owensboro,
Ky., assignors to General Electric Company, a corpora-
tion of New York

Application April 25, 1956, Serial No. 580,647

2 Claims. (Cl. 49—81)

Our invention relates to electric discharge devices and pertains more particularly to new and improved methods for manufacturing electric discharge device envelopes.

Some electric discharge devices comprise an electrode mount structure sealed in an envelope and including a plurality of electrode elements supported in insulated spaced relation between spaced insulators. Often the envelope is fabricated by sealing a closure member or stem in an open end of a glass bulb or the like. The stem is generally constructed with conductive leads extending therethrough and supporting the electrode mount structure which is positioned in the bulb before sealing and is disposed in the bulb portion of the envelope following sealing of the stem thereto.

The mentioned bulbing operation has customarily been accomplished by butt-sealing the open end of the bulb to a planar surface of the stem. Several undesirable effects often result with this type of seal. For example, it has been found that a satisfactory seal generally results when the inner surface of the seal between the bulb and stem is formed as a round fillet flowing smoothly from the bulb portion into the stem portion, and when this fillet is not of such magnitude as to extend into the fillets generally formed around the leads extending through the stem. Often in tubes constructed by the butt-sealing method re-entrant angles resulted at the inner surfaces of the seals, or portions of the seals flowed too close to the leads with the result that the seals failed, under sudden temperature changes, such as those encountered in standard thermoshock tests and during tinning of the leads.

Accordingly, a primary object of the present invention is to provide new and improved methods of manufacturing electric discharge device envelopes.

Another object of the present invention is to provide new and improved methods for reducing the amount of production loss due to failure of seals between bulbs and lead stems.

Another object of the present invention is to provide new and improved methods for obtaining improved seals adapted for withstanding considerable temperature changes.

Another object of the present invention is to provide new and improved methods for sealing mount structures in electric discharge devices whereby the assembly of the devices is facilitated and the enveloping operation is expedited.

Further objects and advantages of our invention will become apparent as the following description proceeds and the features of novelty which characterize our invention will be pointed out with particularity in the claims annexed to and forming part of this specification.

In carrying out the objects of the present invention we provide a tube bulb including a flared open end. The flared end enables the stem to engage the inner surface of the bulb to provide for a desirable type of seal. Subsequent to such engagement, the bulb end and stem are heated to a fusion consistency, after which a force is applied between the stem and bulb whereby the stem and bulb end are fused with an action causing excess material to flow outwardly rather than inwardly toward the stem leads. Thereafter, the stem is rolled whereby the excess material is desirably distributed externally of the bulb.

For a better understanding of the present invention, ref-

2

erence may be had to the accompanying drawing wherein:

Figure 1 is an enlarged, perspective, exploded view illustrating certain features of the present invention;

Figure 2 is an enlarged, fragmentary, sectional view illustrating the heating step of the present invention;

Figure 3 is an enlarged, fragmentary, sectional view illustrating another step of the sealing operation;

Figure 4 is an enlarged, fragmentary, partially sectionalized view illustrating the rolling step in the method of the present invention; and

Figure 5 is an enlarged, fragmentary, partially sectionalized view of a modified form of the present invention.

Referring to Figure 1, there is shown an electric discharge device generally designated 1 and constructed to include a bulb structure 2 formed of a suitably insulative material such as glass. The bulb 2 includes a substantially cylindrical body portion 3, an exhaust tubulation 4, and a slightly flared open-end portion generally designated 5.

During manufacture of the device, and, specifically during the bulbing or enveloping operation an electrode mount structure generally designated 6 is inserted in the cylindrical body portion 3 of the bulb 2.

The mount structure 6 includes a plurality of mutually spaced electrodes supported by and between a spaced pair of insulators 7. The insulators 7 may be formed of mica and include radially extending points or snubber portions 8 adapted for causing a snug fit or interference between the insulator and the inner wall of the envelope 2 when the mount 6 is inserted therein. The snug fit is required to control shock and vibration of the mount in the bulb and thereby minimize microphonics and other undesirable effects generally resulting from relative movement between the envelope and mount structure.

The mount structure 6 is supported on a closure or stem member 9 by being secured, as by welding, to portions of conductive leads generally designated 10, which extend through the stem 9 in a suitably sealed manner and are adapted for providing electrical connections between circuits external of the tube and the various electrode elements of the tube mount. The stem 9 is formed of a suitable insulative material, such as glass, to provide a substantially solid disk and, in a manner to be described hereinafter, is adapted for being sealed to the open end of the bulb 2 for completing the structure whereby the electrode mount is enveloped. The stem 9 is formed to include a raised planar central portion 9a and an annular rib 9b which cooperate to provide an annular shoulder

or step 9c. The purpose for this construction will be brought out in detail hereinafter. The stem 9 also includes fillets 11 formed in a conventional manner about the leads 10 on the inner surface of the stem.

The flare 5 on the open end of the bulb is such that it provides an internal surface greater in diameter than the diameter defined by the points 8 on the insulators 7. Thus, when the mount 5 is inserted into the cylindrical portion of the envelope during the start of the bulbing operation, the points 8 contact the inner surface of the bulb and are guided into the bulb on an inclined plane.

Thus, bending forces on the point 8 resulting during insertion of the mount into the bulb increase only gradually as the insertion is carried out. This results in the points 8 bending in a manner illustrated in Figure 2 and without breaking. Thus, loose mica particles are not broken from the points. This results in minimization of undesired loose particles in the bulb and avoids weakening of the points whereby the tight fit of the mount in the bulb would be adversely affected.

Thus, the flare 5 avoids breaking of the mica points and the various undesired effects thereof. Additionally, it will be seen from the foregoing description that this

is accomplished without reliance upon a polishing operation which without the flare would undesirably reduce the diameter of the open end of the bulb.

Following insertion of the mount in the tube bulb in the manner described above, the stem 9 is moved down into the position shown in Figure 2 wherein the outer edge of the portion 9a or the upper edge of the step 9c of the stem makes peripheral contact with the internal surface of the flared portion 5 of the bulb. Desirably, the angle of flare of the portion 5 is such that the step 9c is received in and makes contact with the surface portion of the flare 5 interiorly of a median portion of the envelope wall as shown by the dot and dash line, Figure 2. With the bulb and stem in these relative positions, heat is applied thereto, as by the application of a plurality of circumferentially arrayed pin fires, two of which are indicated at 12. Thus, the contiguous portions of the bulb and stem are softened to a consistency whereat they are adapted for flowing and fusing to provide a desired seal between the stem and bulb.

With the stem 9 and flared portion 5 of the bulb heated to the just-described consistency, a force is applied to the stem as by means of an applicator illustrated in outline in Figure 3 and generally designated 13. Thus, the stem is moved inwardly toward the envelope for causing a fusion thereof and a mushing out or outward and upward flow of the excess glass of the bulb edge into the step 9c of the stem in the manner indicated at 14 in Figure 3. This desired flow of the excess bulb glass is facilitated by the flare of the end of the bulb and the cooperation thereof with the edge of the portion 9a when the bulb and stem are moved toward each other. This type of seal might be described as a combination lap-butt seal since it is characterized by a butt seal between a portion of the flared end of the bulb and the edge of the portion 9a of the stem as well as a lap seal about the step 9c of the stem. Thus, some of the desirable attributes of both lap and butt seals are obtained. In this manner, sealing of the stem to the bulb is effected with a desired smoothly rounded or large-radius fillet in the sealing area and generally indicated at 15. Additionally, the described sealing operation avoids undesired flow of the excess material 14 inwardly toward the fillets 11 formed about the leads 10.

The rounded fillet 15 and the absence of sealing material interconnecting the lead fillets 11 and the sealing region insures a high-strength seal and adapts the seal for better withstanding thermoshocking, for testing the seal and which generally involves holding the device in 100° C. water for approximately 15 seconds and then dropping it into ice water for 5 seconds.

For purposes of enhancing the appearance of the device and improving the quality of the seal obtained in the just-described manner, we distribute the excess material 14 over the lateral surface of the stem 9. To this end and while the excess material 14 is in the softened condition, the tube envelope is rolled between a pair of counter-rotating elements 16, in the manner illustrated in Figure 4. As also illustrated in Figure 4, the rolling operation distributes the excess material 14 by causing it to flow upwardly over the lateral surface of the stem and toward the outer side of the stem. Thus, we enhance the appearance of the sealed portion of the device and improve the seal while preserving the desired internal round fillet 15.

In Figure 5 is illustrated a modified form of the present invention. In this form there is provided a stem 17 comprising a disk-like member which may be formed of the same material as the stem 9 described above but which need not include the portions 9a-9c described above. Cooperating with the member 17 is a bulb 18 including a flared open end portion 19. The angle of flare of the portion 19 is such as to enable a substantial portion of the stem to be received in the flare in the manner illustrated.

The members are heated to fusion consistencies while

in the relative positions shown in Figure 5 whereby fusion occurs and excess bulb material is caused to flow around the lateral portions of the stem member thereby to effect a lap-seal and a desired smoothly rounded or large-radius fillet similar to that designated 15 in Figure 3. Subsequently, the seal may be rolled desirably to distribute the excess material about the lateral portions of the stem while preserving the desired internal fillet in the manner illustrated in Figure 4.

It will be seen from the foregoing that the provision of the bulb structure including the flared open end precludes the necessity of reliance upon a fire-polishing operation to insure against breakage of mica points, reduces cost of production, expedites the bulbing operation and minimizes conditions tending to cause presence of loose mica particles in the bulb structure. By minimizing the presence of loose mica particles in the structure mount finished tube shrinkage or production loss due to such particles is minimized. Additionally, avoidance of breakage of the mica points enables such points to fulfill their intended purpose of providing a tight fit of the mount in the tube bulb thereby to minimize microphonics and other undesirable effects resulting from a loose fit. Furthermore, the seal provided as described above is adapted for reducing sealing failures by withstanding the thermoshock test to which many tubes are customarily subjected during the exhaust operation following the sealing operation.

While we have shown and described a specific embodiment of our invention we do not desire our invention to be limited to the particular form shown and described, and we intend by the appended claims to cover all modifications within the spirit and scope of our invention.

What we claim as new and desire to secure by Letters Patent of the United States is:

1. The method of sealing a closure member in the open end of a glass bulb comprising the steps of preforming the open end of said bulb to provide a flare, thereafter partially inserting said closure member in said flared open end of said bulb and only line contacting the internal flared surface of said open end of said bulb with said closure member at a line of contact inwardly of the edge of said bulb, then heating said flared end and closure member for effecting fusion thereof at the line of contact, and causing laterally outward flow of excess flowing material over the lateral external surface portion of said closure member by applying a longitudinally directed externally applied force between said bulb and closure member.

2. The method of sealing a closure member in the open end of a glass bulb comprising the steps of preforming the open end of said bulb, thereafter partially inserting said closure member in said flared open end of said bulb and only line contacting the internal flared surface of said open end of said bulb with said closure member at a line of contact disposed inwardly of said open end of said bulb, then heating said flared end and closure member for effecting fusion thereof at the line of contact, causing outward flow of excess flowing material over the lateral external surface portion of said closure member by applying a longitudinally directed externally applied force between said bulb and closure member, and distributing the major portion of excess flowing material smoothly over the external surface of said closure member by rolling the resultant fused seal.
